United States Patent Office

Des. 201,829
Patented Aug. 3, 1965

201,829

PROTRACTOR

Joseph O. Marcoline, 9137 S. 89th Ave.,
Hickory Hills, Ill.

Filed May 13, 1963, Ser. No. 74,864

Term of patent 14 years

(Cl. D52—6)

FIG. 1 is a top plan view of the protractor showing my new design;

FIG. 2 is a side elevational or edge view of the protractor;

FIG. 3 is a bottom plan view of the protractor; and

FIG. 4 is an enlarged sectional view taken along the line 4—4 of FIG. 1.

I claim:

The ornamental design for a protractor, substantially as shown.
